ALKYLATION OF ETHYLENE MIXED FEEDS

Charles S. Lynch, Plainfield, and Howard G. Codet, Mountainside, N. J., assignors to Standard Oil Development Company, a corporation of Delaware

Application May 25, 1943, Serial No. 488,344

6 Claims. (Cl. 260—683.4)

1

The present invention relates to improvements in the art of alkylating ethylene mixed feeds, and more particularly, it relates to a continuous operation of catalytically alkylating ethylene with isoparaffins in which the ethylene feed stock is mixed with other hydrocarbons and gases and in which the alkylation is accomplished in a manner which is cheaper than has been possible heretofore.

Recently it has been found that ethylene may be alkylated with isobutane to form hydrocarbons boiling within the gasoline range, of high octane number, including 2,3-dimethyl butane. It has been found in connection with these researches that the catalyst prepared by contacting the isoparaffin and the olefin with aluminum chloride for an extended period of time is a brown, mobile liquid which apparently is an aluminum chloride hydrocarbon complex, which is an active catalyst possessing a long life and is otherwise satisfactory. It has further been found in connection with these prior researches that the alkylation may be carried out at ordinary atmospheric temperatures or above. For example, the alkylation may be carried out at temperatures from 65°-200° F. with a range of 90-125° F. preferred. It has further been found that a small amount of volatile halide incorporated with the isobutane feed greatly improves the quality and the yields. Thus, from 1 to 15% of ethyl chloride or methyl chloride based on the isobutane or other isoparaffin greatly increases the efficiency of the process. About 5-10 volume per cent of ethyl chloride gives the best results. Further, it has been found that pressures of from 100-1000 lbs./sq. in. give good results with pressures of the order of 200-300 lbs. preferred. The researches have also revealed that the fresh feed to the reaction zone should have an excess of the isoparaffin, that is to say, best results are obtainable when the fresh feed contains 3 mols of isoparaffin to each mol of olefin. With respect to the amount of aluminum chloride, it has been found that by maintaining from 3 to 100, and preferably about 20 weight per cent of aluminum chloride in the reactor gives optimum results. Under the conditions stated, numerous runs have demonstrated that when working at its best, the foregoing process is adapted to produce an alkylate over 60 volume per cent of which contains C₆ hydrocarbons, including 2,3-dimethyl butane. 2,3-dimethyl butane is a hydrocarbon which has a high octane number but is particularly valuable because of its excellent rich mixture performance in a supercharged engine.

2

Our present invention relates to that phase of the above indicated process which includes separating the ethylene from the gases with which it is associated as it is fed to the system before contacting the catalyst in the alkylation process. In other words, in a commercial refinery the normal C₂ or ethylene fraction will be associated with neighboring hydrocarbons and hydrogen. In other words, the C₂ hydrocarbons will contain in addition to the desired olefin, methane, ethane, and hydrogen. The paraffins, of course, are inert, and if they flow through the system with the ethylene during the reaction, they will eventually have to be eliminated and their processing and elimination uselessly, of course, requires additional facilities and utilities.

In brief compass, we have devised a process for eliminating the unwanted hydrocarbons in the ethylene feed, in a relatively simple and expeditious manner as will more fully appear hereinafter.

In the accompanying drawing we have shown a flow plan indicating a continuous process for alkylating ethylene with isobutane, including the features hereinbefore mentioned.

Referring in detail to the drawing, we shall describe a preferred method of alkylating ethylene with isobutane in the presence of aluminum chloride hydrocarbon complex so that a better understanding of our invention may be had.

1 is a reactor which, as indicated in the drawing, may be an elongated, cylindrical vessel packed with a material such as Raschig rings. Superposed on reaction vessel 1 is a settler 2 carrying a pressure gauge 3 disposed in a vent line 5 carrying a liquid level control valve 10. Disposed at the side of the reactor 1 is a vessel or receptacle 20 in which is contained aluminum chloride, and the feed stock, as will subsequently appear, passes through this container where it absorbs or otherwise acquires aluminum chloride and then flows into the reactor. The ethylene feed enters the system through a line 25 and the isobutane enters through line 28, the latter being in a liquid condition. At the start of the operation, the isobutane is first introduced into the empty system through line 28, flows through a scrubber 30, thence is withdrawn through line 32 and pumped by pump 35 through line 36 into reactor 1 until the column is nearly filled with liquefied isobutane. The ethylene feed is introduced through line 25 as a gas to scrubber 30 where it is absorbed and passes via line 32, pump 35 and line 36 into the reactor 1 until the isobutane is about 55 half saturated with respect to ethylene. The eth-

ylene and isobutane pass upwardly to settler 2 and then are withdrawn through recycle line 40 and returned to the tower 30 for recycling via line 32, but now the recycle stream passes through line 38 and thence through the aluminum chloride receptacle 20 and thence passes into the tower 1.

After the passage of 3-4 hours, the aluminum chloride will have reacted with the hydrocarbons to form the aforementioned aluminum chloride-hydrocarbon complex, which is the active catalyst for the alkylation process, and after this "induction" period during which the catalyst is formed, product may be withdrawn through line 12 and delivered to fractionating and distilling equipment (not shown) to recover the desired products. There will come a time when the material recycled through 20 must be directed to another container 20a which contains fresh aluminum chloride, the latter container being similar in construction 20, and thence passed into the reactor 1 as before. The container 20 is thoroughly cleaned and recharged with aluminum chloride for subsequent use in the process. In other words, the preferred method of operating the process is to provide two or more containers 20 and 20a and after one has been in use for some time, it will be withdrawn from the circulating system, thoroughly cleaned and recharged with fresh aluminum chloride. The other container will meanwhile be on stream. The use of two or more containers 20 maintains continuity of operation even though it is necessary to add aluminum chloride periodically to the system to maintain the catalyst activity as previously indicated. It will be noted that a portion of the recycle product in line 32 may bypass the container 20 or 20a and pass directly into the reactor 1 through line 36. We maintain a consumption of aluminum chloride in our process varying from 0.04 to 0.08 lb. of $AlCl_3$ per gallon of alkylate.

There is another point with respect to the operation of the process and it is this, viz., that when the reactor becomes filled with catalyst, the excess passes into settler 2, from which it may be withdrawn by draw-off pipe 8. Actually, however, the system may be operated 100 hours or more before it is necessary to withdraw spent catalyst through pipe 8.

Except for the manner of introducing the feed stocks, we have indicated the development of the alkylation process up to the time of our invention, which invention will now be described in detail. Heretofore, in operating the process described, the ethylene feed and the isobutane feed are not fed to the system in the manner we have indicated in the drawing but are charged directly to the reactor, and therefore our improvement comprises, principally, the interposition of the scrubber 30 into the system. The mixed feed entering the said scrubber at 25 contains hydrogen, methane, ethylene, and possibly ethane, and contacts therein the isobutane which enters through line 28. The isobutane becomes saturated, of course, with respect to hydrogen, methane, ethylene, and ethane. The ethylene in the course of the reaction is continually removed in reactor 1, but the hydrogen, methane and ethane are unchanged and consequently the recycle stream in 40 entering scrubber 30, after the process has been in operation for a sufficient period of time, is saturated with respect to all of the components entering 25, except ethylene, and hence only the ethylene is dissolved out of the

entering feed while the other components pass up the tower and may be withdrawn through a vent pipe 50. It is obvious that this is a desirable method of operating since the removal of hydrogen, methane, ethane, and the like, at the beginning of the operation, makes it unnecessary to circulate these inert materials through the whole system, including the fractionation and distillation equipment in which the product stream 12 is subsequently treated. Thus, by scrubbing the fresh feed with a recycle stream saturated with respect to the unwanted components of the ethylene fresh feed, we are able to reject at once from the system inert materials, such as methane, ethane, hydrogen, and the like, in a simple and expeditious manner.

Our process possesses particular utility in the processing of an ethylene feed stock which contains a minor quantity of ethylene, say from 30-40%, such as is obtained, for example, in steam cracking of hydrocarbons. However, our process could be used for feed stocks containing as low as 10% ethylene in the feed entering through line 25 and this low concentration of ethylene would be highly impractical in an alkylation process where a large preponderance of inert material continuously passed through the system. The temperature of the liquid in the recycle stream is from 50° to 200° F., preferably from 75° to 125° F., and the pressure is from 100 to 1000 lbs./sq. in., preferably from 200 to 300 lbs./sq. in.

In operating our process, as in the previous development of this process, we maintain a molecular excess of isobutane over the ethylene. Preferably we maintain 3 to 100 mols of isobutane per mol of ethylene in the reaction zone. The recycle ratio, i. e., the ratio of recycled product to fresh feed is from 1 to 30 volumes of recycle product per volume of fresh feed (i. e., newly added ethylene and isobutane, disregarding the undesired constituents in the ethylene feed). When operating at its best, very little catalyst is in the recycle stream, viz., less than 0.04 weight per cent when operating at 110° F.

We have described in detail the application of our invention to the alkylation of ethylene and isobutane. It is to be understood that the same principle may apply to the alkylation of propylene or butylene where the propylene or butylene feeds are mixed or diluted with relatively large quantities of other gaseous materials. The removal of propane in the scrubbing step is possible when, as is usually the case, the pressures exceed 125 lbs./sq. in. in the system.

What we claim is:

1. In the continuous alkylation of olefins with isoparaffins conducted in the presence of an aluminum chloride-hydrocarbon complex formed in situ during the operation of the process, the improvement which comprises first forcing a mixed feed containing a minor proportion of ethylene with an isoparaffin through a reaction zone containing the said aluminum chloride-hydrocarbon complex, permitting the feed stock and the catalyst to remain in contact with each other for a sufficient period of time to effect the desired conversion, withdrawing a product stream, simultaneously withdrawing a recycle stream containing isobutane and small amount of alkylate, passing the recycle stream into a scrubbing zone, forcing the mixed feed containing a minor proportion of ethylene in countercurrent contact with the recycle stream whereupon the recycle stream becomes saturated with undesired com-

ponents of the mixed feed containing ethylene, withdrawing the recycle stream enriched with ethylene from the scrubbing zone and returning the same with added isobutane to the reaction zone, continuing the flow of materials in the manner indicated, thus causing mixed ethylene feed, after the recycle stream has become saturated with undesired components of the fresh feed, to contact said recycle stream whereby said undesired components are rejected by the recycle stream in the scrubbing zone and are adapted to be withdrawn from the scrubbing zone and thus separated from the desired ethylene dissolved in said recycle stream.

2. In the continuous alkylation of ethylene with isobutane in a continuous operation employing a hydrocarbon AlCl_3 complex catalyst, the improvement which comprises feeding a hydrocarbon stream containing ethylene and undesired components to a scrubbing zone, feeding a recycle product stream substantially saturated with respect to undesired components of the feed to said scrubbing zone, contacting said hydrocarbon stream with said recycled product in said scrub-

bing zone whereby substantially only ethylene is dissolved in said recycled product, withdrawing the undesired components of said hydrocarbon stream from said scrubbing zone, conducting the recycled product containing dissolved ethylene with added isobutane to a reaction zone containing the said hydrocarbon- AlCl_3 complex catalyst, permitting the ethylene and isobutane to contact each other and the catalyst at elevated temperatures and pressures.

3. The method of claim 2 in which the temperature in scrubbing zone is from about 75 to 200° F.

4. The method of claim 2 in which the pressure in the scrubbing zone is from 200 to 400 lbs./sq. in.

5. The method of claim 2 in which the ethylene feed contains from 50 to 90% hydrocarbons other than ethylene.

6. The method of claim 2 in which the AlCl_3 consumption is from 0.04 to 0.08 lbs. AlCl_3 per gallon of alkylate produced.
